INVENTOR :

Thomas S. Ramsdell,

By Attorneys,

Fraser, Myers & Manley

UNITED STATES PATENT OFFICE.

THOMAS S. RAMSDELL, OF GREAT BARRINGTON, MASSACHUSETTS.

PIPE CLEANER.

Application filed October 31, 1925. Serial No. 65,928.

The present invention relates to a pipe cleaner and aims to provide a simple, practicable and efficient device for removing the incrustations or deposits formed within the 5 bowls of smokers' pipes, and one which will be equally well adapted for cleaning pipe bowls of various shapes and sizes.

According to my present invention I provide a device of the character described 10 which consists of a self-centering frame of preferably conical form adapted to engage over the outer wall of a pipe bowl when pressed over the mouth thereof, the top of the frame being formed with a central opening 15 in which is mounted a carrier for a cutter adapted to be moved both longitudinally and rotatably with respect to the frame, and means on said frame for holding it against movement during the act of cleaning out or removing the incrustation from 20 the interior of the pipe bowl. The invention also resides in other specific details of improvement which will be hereinafter more fully described.

25 The accompanying drawing shows two embodiments of my invention wherein:

Figure 1 is a perspective view of the device with a part thereof broken away to disclose the cutter.

30 Fig. 2 is a longitudinal section of a pipe having the device of Fig. 1 applied thereto.

Fig. 3 is a transverse section of a pipe showing a modification of the device shown in Fig. 1 applied thereto.

35 Fig. 4 is a fractional side elevation of Fig. 3.

Fig. 5 is a plan view of the cutter device used with my invention.

40 Figs. 6 and 7 are details of a modified form of cutter device used with my invention.

Referring to the drawings let A indicate a smoker's pipe of any conventional form having a tobacco receiving bowl B, the interior of which is shown coated with an incrustation or deposit C. This deposit, it will be understood, if not removed, will continue to grow, thereby reducing the capacity of the pipe bowl and also tend to close up or seal the passage α through the pipe stem. It is therefore advisable to remove this deposit from time to time, and according to the present invention I have provided an improved pipe cleaner for accomplishing this result.

In Figs. 1 and 2 of the drawings my pipe cleaner is shown as consisting of a frame D which is preferably of internal conical form so as to adapt it to fit over pipe bowls of different diameters. The conical form of the frame also serves to center the frame with respect to the bowl when applied thereto. The frame at its top is formed with a wall E having a central opening F in which is mounted a cutter carrier G adapted to be moved both axially and rotatably with respect to the frame D. As herein shown, this movement of the cutter carrier is accomplished through the provision of co-operating screw threads on the exterior of said carrier and the interior of the opening F. Obviously other means for accomplishing this result may be resorted to. The frame D, it will be understood, 60 may be formed of metal, fibre or other suitable substantially rigid material, and in order that the cutter carrier G may be suitably supported and a more sturdy construction result I prefer to form the top of the frame E with a bushing extension E', which, 65 it will be obvious, will also be internally threaded as is the top E. The interior wall of the frame D may also be lined with a thin piece of leather or other soft material 70 to prevent marring of the pipe bowl.

The cutter carrier G is provided at its inner end with a cutter H herein shown as having cutter blades h, and at its outer end with a manipulating knob J, rotation of which causes longitudinal or axial movement 75 of the cutter H with respect to the frame D. I prefer to have the cutter H removably mounted on the carrier G, and provide a number of cutters of different sizes whereby pipe bowls of various internal diameters may 80 be reamed out to their proper size. The cutter H is accordingly formed with a central threaded opening h' adapted to engage over a reduced threaded end g on the carrier G, and the cutter held in place thereon by a screw K entering the end of the reduced shank and engaging the bottom face of the cutter. An alternative method of securing the cutter to the carrier is shown in Figs. 6 85 and 7, wherein the cutter H' is formed with a central square opening h² adapted to fit over a reduced square shank g' formed on the inner end of the carrier G, the cutter being held thereon by a screw K in the same manner as shown in Figs. 1 and 3.

In order that the pipe cleaner may be suitably held upon the pipe bowl during the cleaning operation the frame D is provided with a pair of oppositely disposed hook-like members L adapted to be grasped by the fingers of the operator while holding the bottom of the bowl of the pipe in the palm of his hand.

In Figs. 3 and 4 I have shown an alternative construction for accomplishing the same result, wherein the hook-like members L' pivotally support a U-shaped member or bail M which is adapted to assume a position embracing the lower portion of the bowl and which is provided at its central portion with an adjustable clamping member N adapted to engage the bottom of the bowl to draw the frame downwardly over the top of the bowl. As herein shown, said clamping member N consists of a screw-threaded shank n threaded through a bushing enlargement m formed on the U-shaped member, the inner end of the threaded shank having a clamping plate n' swiveled thereto and the outer end of said shank having a manipulating knob n². If desired, the engaging face of the clamping plate n' may be covered with a piece of felt n³ or other soft material to prevent scratching or mar-

ring of the polish on the pipe bowl. In use the frame D is applied over the mouth of the pipe bowl which is then taken in the palm of the hand, two fingers of which are then caused to straddle the hook-like members L to press the frame downwardly over, and hold it against movement on the pipe bowl. The knob J is then turned to the right which causes inward movement of the cutter H, which, as it progresses, will cut away the incrustation C, as shown in Fig. 2. After the incrustation is cut away, the hold on the hook-like members is released and the pipe cleaner lifted off from the pipe bowl. In the modification shown in Figs. 3 and 4, instead of the operator straddling the members L' with his fingers, the U-shaped member is brought down into position below the pipe bowl and the knob n² is turned to move the clamp n' into engagement with the bottom of the bowl to draw the frame downwardly over the top thereof. After the cutting away operation is completed, the clamp n' must be released from its engagement through turning of the knob n² in the opposite direction, after which the U-shaped member M is raised about its pivotal connection to clear the pipe bowl and the device as a whole is removed therefrom.

From the foregoing description it will be appreciated that I have provided an exceedingly simple, practicable and efficient pipe cleaner adapted for use on smokers' pipes of different shapes and sizes, the only occasional adjustment being the change from

one size of cutter to another where the interior diameters of the bowls to be cleaned are very different.

While I have shown and described two specific embodiments of my invention I desire it to be understood that various changes in mechanical construction and shapes of parts employed may be resorted to without departing from the spirit of my invention, as embraced in the appended claims.

What I claim is:

1. A pipe cleaner for smokers' pipes, comprising a frame adapted to engage over the outer wall of the pipe bowl when pressed over the open top thereof, a cutter centrally mounted on said frame, adapted to be moved both axially and rotatably with respect thereto when the frame is in engagement with the pipe bowl and means for holding the frame against movement on the pipe bowl.

2. A pipe cleaner for smokers' pipes, comprising a self-centering frame adapted to engage over the mouth of the pipe bowl, a cutter carried by said frame and movable both axially and rotatably with respect thereto when the frame is in engagement with the pipe bowl, and means for holding the frame against movement on the pipe bowl.

3. A pipe cleaner for smokers' pipes, comprising a frame having inclined sides adapted to engage over the outer wall of the pipe bowl when pressed over the open top thereof, a cutter centrally mounted on said frame, adapted to be moved both axially and rotatably with respect thereto when the frame is in engagement with the pipe bowl, and means on the frame engageable by the fingers of the user for holding the frame against movement of the pipe bowl.

4. A pipe cleaner for smokers' pipes, comprising a frame having a conical wall adapted to engage over the outer wall of the pipe bowl when pressed over the open top thereof, a top wall having a screw-threaded central opening therein, a threaded shank extending through said opening having an operating member at one end and a cutter at the other end thereof, and means for holding the frame against movement on the pipe bowl.

5. A pipe cleaner for smokers' pipes, comprising a frame having a conical wall adapted to engage over the outer wall of the pipe bowl when pressed over the open top thereof, a top wall having a screw-threaded central opening therein, a threaded shank extending through said opening having an operating member at one end and a removable cutter at the other end thereof, and a pair of hook-like members carried by the frame and engageable by the fingers of the user for holding the frame against movement on the pipe bowl.

6. A pipe cleaner for smokers' pipes, comprising a frame adapted to engage over the

outer wall of the pipe bowl when pressed over the open top thereof, a cutter centrally mounted on said frame, adapted to be moved both axially and rotatably with respect thereto and means for holding the frame against movement on the pipe bowl comprising a U-shaped member pivotally carried by the frame adapted to assume a position below the pipe bowl when the cleaner is ap-

plied thereto, and an adjustable clamping member carried by said U-shaped member adapted to draw the frame downwardly over the top of the pipe bowl into holding engagement therewith. 10

In witness whereof, I have hereunto signed my name. 15

THOMAS S. RAMSDELL.
